[57] CLAIM

The ornamental design for the jacket for air tool, as shown and described.

DESCRIPTION

FIG. 1 is a perspective view of the jacket for air tool constituting our new design;

FIG. 2 is a side view of one side thereof, the other side being identical;

FIG. 3 is a top plan view thereof;

FIG. 4 is a bottom plan view thereof;

FIG. 5 is an end view of one end thereof; and,

FIG. 6 is an end view of the other end thereof.

The broken line showings of a portions of a wrench are environmental only and form no part of the claimed design.
